CLAIM

The ornamental design for a dual sensor motion detector, as shown and described.

DESCRIPTION

FIG. 1 is a top-front perspective view of the dual sensor motion detector showing my new design;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a top-back perspective view thereof; and,

FIG. 9 is a top-front perspective view thereof, shown in an alternate position.

The features in the figures shown in broken lines form no part of the claimed design.
